ATTORNEY.

UNITED STATES PATENT OFFICE.

THOMAS J. EDWARDS, OF AKRON, OHIO.

DESIGN FOR AN ELASTIC VEHICLE-TIRE.

52,731.

Specification for Design.

Patented Dec. 10, 1918.

Application filed October 11, 1918. Serial No. 257,798. Term of patent 14 years.

To all whom it may concern:

Be it known that I, THOMAS J. EDWARDS, a citizen of the United States, residing at Akron, in the county of Summit and State of Ohio, have invented a new, original, and ornamental Design for Elastic Vehicle-Tires, of which the following is a specification, reference being had to the accompanying drawings, forming a part thereof.

In the drawings,

Figure 1 is a plan view of a portion of an elastic vehicle tire embodying this invention and my new design, and

Fig. 2 is a transverse sectional view taken approximately on line 2 of Fig. 1.

I claim—

The ornamental design for an elastic vehicle tire, as shown.

THOMAS J. EDWARDS.
